UNITED STATES PATENT OFFICE.

ROBERT G. RICE, OF GEORGETOWN, TEXAS.

SCREEN.

SPECIFICATION forming part of Letters Patent No. 363,258, dated May 17, 1887.

Application filed May 24, 1886. Serial No. 203,130. (No model.)

To all whom it may concern:

Be it known that I, ROBERT G. RICE, a citizen of the United States of America, residing at Georgetown, in the county of Williamson 5 and State of Texas, have invented certain new and useful Improvements in Screens, of which the following is a specification, reference being had therein to the accompanying drawings.

My invention relates to an improvement in 10 screen-protectors for the protection of the person while sleeping or in a reclining posture; and it consists in the peculiar construction, combination, and arrangement of the parts, substantially as hereinafter more fully shown 15 and described.

In the accompanying drawings, Figure 1 is 20 a side elevation embodying my improvement in screen-protectors. Fig. 2 is a sectional view of the same, and Figs. 3 and 4 are detail views 25 of the device.

The object of my invention is not only to 25 protect the exposed portions of the persons of adults and infants from the annoyance of flies and mosquitoes, &c., while sleeping, but also to provide, as an adjunct thereof a book-rest for the convenience of reading in a reclining posture, and mechanism for hoisting the device out of the way when not in use.

In the construction of my screen-protector 30 the size of the device may be determined by the purpose to which it is to be applied, and a distinction be made between those for use of adults and those for infants, the upper and exposed portion of the person of adults only 35 needing protection, while the device may also be employed for thus protecting infants, and also protecting them from cold-air drafts by throwing over the frame a shawl or other suitable article.

40 The screen-frame A is supported upon its curved horizontal wire base B, the ends of the strand being projected through eyes a, provided one at each end of the arch-wire C.

Arch-wire C has coiled around the center of 45 its arch and projecting therefrom the longitudinal wire D, which is curved to form the oval-shaped head of the device, and the opposite end of the longitudinal wire D is formed into a loop which incasps, and is thus secured 50 to the strand of the wire base B.

The ends of central arch-wire, E, are also looped to incasps the strand of wire base B,

and it is braced where it intersects longitudinal wire D by means of the auxiliary strand F, with which these intersecting wires are tied. 55

The auxiliary strand F is finer in degree than the other strands employed, and its ends entwine and are secured to base wire B at points intermediately between longitudinal wire D and central arch-wire, E. Auxiliary strand F 60 thus arranged serves not only to tie said intersecting wires, but it is curved at F' F'' to complete the curved conformation of the head of the device, the netting G, with which the frame A is inclosed, being secured thereto, as shown. 65

The frame-work of the screen may be constructed of brass or galvanized wire, or wire having strands covered with any suitable fabric or material.

The netting or gauze G is sewed or otherwise secured to the wire base B, and extends out around and beyond the same a sufficient distance to prevent ingress of flies through any apertures caused by inequalities of surface beneath the same, and it also extends out beyond 70 the front end of the frame a sufficient distance to enable the opening in that end to be closed therewith. For the convenience of adults who may desire to read thus protected, book-holder H may be employed in connection with my 75 screen-protector. It consists of the shelf b, having fender d. It is supported by wires e, secured thereto at either end thereof, and terminating in loop f, which is hooked upon longitudinal wire D. 80

The fender d consists of the wooden slat g, having pivotally secured thereto the inwardly-inclined slightly curved metallic springs h. 85

The book is inserted between the back of shelf b and springs h, which retain the leaves 90 of the book in position. The hoisting-cord L is attached to longitudinal wire D and passed over a cord-pulley secured to ceiling to enable the device to be swung up out of the way when out of use. 95

I am aware that it is not new to provide a screen consisting of a frame, upon which is supported netting or gauze extending beyond the sides thereof, said frame being secured in the desired position by means of a cord and pulley, a supporting-bar, or other suitable suspending medium; but my invention is designed as an improvement on such devices, and I dispense with the use of all means for suspend-

ing the screen and provide the same with a base, to which are connected the ends of the wires, over which is placed the gauze or netting, thus always insuring the proper retention of the screen in position, and in addition thereto I secure to the central longitudinal wire the suspending-wires of a book-support comprising a shelf to the front end of which are connected the ends of inwardly-bent springs to for securely retaining the book in position.

It will be seen that the upper end of the supporting-wires is so bent as to give the book holder or support the proper inclination required in reading the book retained therein.

Having thus described my invention, what I claim, and desire to secure by Letters Patent, is—

1. The combination, with the wire frame and the base to which the ends of the wires of said frame are connected, of the auxiliary strands bracing the arch-wire of said frame, and the book-holder having the upper end of its supporting-wires bent and connected to the longi-

tudinal wire of said frame, substantially as shown and described.

2. The book-holder consisting of the shelf, the wires connected to the ends thereof, and having the looped end bent, as stated, and the curved springs secured at one end to the fender of said shelf, substantially as shown and described.

3. The combination, with the screen having a longitudinal wire, of the book-holder, the curved springs connected to the shelf thereof, and the supporting-wires connected to said shelf, having their looped end bent to occupy a vertical plane and the remaining portion inclined rearwardly, substantially as shown and described.

In testimony whereof I affix my signature in presence of two witnesses.

ROBERT G. RICE.
